HINGE CONSTRUCTION

John J. Thomas, Newport News, Va.

Application March 13, 1944, Serial No. 526,248

8 Claims. (Cl. 16—135)

This invention relates to a hinge construction and in accordance with the present invention is particularly adapted for use with trunk lids of automobiles or other lids or doors requiring means to maintain same in open or raised position. However, my improved hinge is not limited to such uses alone, as the novel features thereof may be embodied in hinge structures for various other uses as will appear in the description following.

A primary object of the invention is the provision of a hinge embodying a pair of pivotally connected plates or leaves and wherein one of the plates is pivotally movable relative to the other plate under a resilient and yieldable resistance, and wherein the movable plate is automatically latched in a predetermined angular position relative to the other plate under the yieldable resistance and which resistance may readily be overcome upon pressure on the movable leaf in the opposite direction only to unlatch same and return it to a normal position relative to the other leaf.

A further and more specific object of the invention is the provision of a hinge embodying a pair of pivotally connected plates or leaves and wherein one plate is provided with a yieldable tongue and the other plate provided with a roller movable along the yieldable tongue to deflect the tongue upon relative pivotal movement of the plates, the tongue being non-concentric with the pivotal axis of the plates and yielding upon movement of the roller therealong, and the tongue being provided with a recess or opening at a predetermined point in the length thereof for receiving the roller under the yieldable resistance of the tongue and preventing further travel of the roller whereby the plates are latched by the tongue in a predetermined angular relation.

A still further object of the invention is the provision of a hinge of the above noted character embodying means for locking the plates against angular movement beyond a predetermined angular position thereof and preventing separation of the locking means.

A still further object of the invention is the provision of a hinge structure of the above noted character which is relatively simple in construction, durable, highly efficient in operation and which is capable of being manufactured at relatively low cost in shapes and sizes to meet requirements of use.

These and other objects and advantages of the present invention will be more fully apparent from a study of the following specification and

accompanying drawings wherein like numerals designate like parts throughout.

In the drawings:

5 Figure 1 is a side elevational view of a hinge constructed in accordance with one embodiment of the invention, the hinge being shown with its leaves in angular relation in dot-and-dash lines;

10 Fig. 2 is a bottom plan view of the hinge shown in Fig. 1 with a portion thereof broken away to show the operative relationship of otherwise concealed parts;

15 Fig. 3 is a side elevational view of the hinge shown in operative position on an automobile trunk, the lid of the trunk being in open or raised position;

20 Fig. 4 is a side elevational view of a hinge in accordance with another embodiment of the invention, the hinge being similar in type to that shown in Fig. 1;

25 Fig. 5 is a view of the hinge shown in Fig. 4 but illustrating the hinge with one leaf thereof rotated to the angular position relative to the other leaf where the leaves are latched and held against further angular rotation;

30 Fig. 6 is a fragmental plan view of one part of the latch as observed in the plane of line 6—6 of Fig. 4;

35 Fig. 7 is a vertical sectional view in the plane of line 7—7 of Fig. 5, and showing the relationship of the latching parts;

40 Fig. 8 is a partial longitudinal section in the plane of line 8—8 of Fig. 9 showing the application of the essential features of the invention to a hinge structure embodying a pair of flat directly pivotally connected plates or leaves;

45 Fig. 9 is a top plan view, on a reduced scale of the hinge shown in Fig. 9.

Referring now in detail to the drawings, and first to the embodiment of Figs. 1, 2 and 3, the hinge which is illustrated as especially adapted for use with automobile trunk lids, comprises a flat or plane leaf or plate 10 and a second leaf or plate 11 pivotally connected to the plate 10 in the usual manner as by the pin 12.

50 In order to provide for the proper swinging of the gasket carrying upper end of the lid L to and from the gasket seat 3 as well as to provide clearance for the edge of the body provided with such seat as indicated in Fig. 3, the leaf 11 comprises the curved or offset portion 13 extending a substantial distance from the plane of leaf 10 in the position of Fig. 1 and which merges into the plane portion 14 of the leaf.

55 The leaves 10 and 11 are provided with apertures 15 for the reception of attaching devices by

which the leaves are secured to spacing blocks 16 and 17 carried by the body B and lid L respectively of the automobile trunk, as is clearly illustrated in Fig. 3.

The plate 10 is provided with a curved yieldable tongue 18 which as shown is an integral extension of the plate but which may be constructed separately and suitably secured to the plate as shown for example, in Fig. 8. Cooperating with the yieldable tongue 18 is a roller 19 pivotally supported in the bifurcated end of a lug 20 extending outwardly from the curved leaf portion 13.

The tongue 18 is provided with a rectangular aperture 21 adjacent its free end and the yieldable tongue 18 gradually approaches the pivot axis of the plates from the full line position of roller 19 in Fig. 1 to the aperture 21 whereby upon movement of the roller therewith and toward its free end, the tongue will be increasingly tensioned to provide a yieldable resistance to the movement of the plate 11 to its dot-and-dash line position in Fig. 1 or full line position in Fig. 3. Upon the roller 19 reaching the aperture 21, a circumferential portion thereof will drop into the aperture with the tongue still under tension as indicated by the dot-and-dash lines in Fig. 1, with the result that the leaf 11 will be yieldably latched in raised position whereby to support the lid L or other lid or cover in such position without additional holding means.

The advance edge of the aperture 21 is slightly rounded as indicated in Fig. 1 for facilitating reverse movement of the plate 11 to its normal position relative to the plate 10. While it would be more difficult to move the plate 11 beyond the aperture 21 in the direction of the free end of the tongue than in the reverse direction toward normal position due to the curvature of the tongue, means are provided to positively lock the roller against movement from the aperture 21 toward and over the free end of the tongue. Such means consists in the extreme end of the tongue being curved inwardly as at 18' on a radius substantially smaller than that of the main body portion of the tongue, as is clearly indicated in Figs. 1 and 3. The tongue 18 should of course be formed of a width and thickness dependent upon the load intended to be supported by the plate or leaf 11.

While in the operation of raising the lid L the tongue 18 will be substantially tensioned, the provision of the roller 19 together with the substantial leverage provided by the lid L, slight resistance will be offered but the tensioned tongue upon engagement of the roller within the aperture will be sufficient to maintain the lid in raised position and the tension can be overcome by a relatively light pull downwardly on the lid.

The embodiment of the present invention according to Figs. 4 to 7 is generally similar to that of Figs. 1 to 3 and differs therefrom only in a modified form of locking or holding means to prevent overthrow or passage of the roller over the free end of the yieldable tongue. According to this embodiment, the roller 19 is rotatably supported between the flanges 24 of a bifurcated lug 20.

Each of the flanges 24 is provided with a shoulder 25 adapted to engage the rear edge 26 of the wide portion of a T-shaped aperture 21', the narrow portion receiving a portion of the roller which also extends into the wide portion as indicated in Fig. 5. The advance edges of both the wide and narrow portion of the aperture are pref-

erably bevelled or rounded as indicated in Fig. 5 to facilitate return of the roller to normal position.

The normal position of the hinge plates or leaves 10, 11, is indicated in Fig. 4 and upon swinging the leaf 11 to the position of Fig. 5 the roller 19 drops into the aperture 21' and the shoulders 25 engage the edge 26 of the aperture, whereby the roller and accordingly the plate 11 is positively stopped or locked from further movement toward the free end of the tongue.

In Figs. 8 and 9 are illustrated the cooperative structural features of Figs. 4 to 7 in a hinge embodying plates 10' and 11' of usual form and directly pivotally connected by the pin 12. This form of hinge may find desirable application in uses other than automobile trunk lids and may be attached to normally abutting movable and immovable parts by recessing portions projecting to either side of the plane of the leaves in such parts.

In this form of hinge the roller 19 is supported between the flanges 24 of a lug 20'' suitably secured to the plate 11' while the yieldable tongue 18' has one end thereof suitably secured to the plate 10'. The lug 20'' extends parallel with the plate 11' and the plate 10' is provided with a hood portion 28 for normally receiving the roller 19.

While several embodiments of the invention are disclosed they are all generally similar in construction as well as in operation, each embodying a yieldable tongue carried by one plate or leaf, a roller carried by the other plate or leaf, an aperture in the tongue adjacent the free end thereof for engagement by the roller, and stop means for preventing movement of the roller over the free end of the tongue.

While I have disclosed but certain specific embodiments of my invention, such are to be considered as illustrative only, and not restrictive, the scope of the invention being defined in the subjoined claims.

What I claim and desire to secure by U. S. Letters Patent is:

1. A hinge construction comprising a pair of pivotally connected plates, an arcuate resilient and yieldable tongue projecting in the form of a single uniformly curving strip from one of the plates in eccentric relation to the pivotal connection of the plates and having a free end, a bifurcated lug supported by the other plate and including spaced flanges, a roller rotatably supported between the flanges and movable along the tongue upon relative pivotal movement of the plates for gradually tensioning the tongue as it moves toward the free end thereof, an aperture in the tongue adjacent the free end thereof for receiving a portion of the roller to yieldably latch the plates in predetermined angular relation, and a shoulder on one of said flanges for engaging the rear edge of the aperture upon reception of the roller therein to hold the roller against movement over the free end of the tongue.

2. A hinge construction according to claim 1 wherein the tongue supporting plate is provided with a recess and wherein said lug is substantially parallel with its supporting plate for reception of the roller in the recess in a parallel relation of the plates.

3. A hinge construction comprising a pair of pivotally connected plates, an arcuate resilient and yieldable tongue projecting in the form of a single curved strip from one of said plates in eccentric relation to the pivotal connection of the

plates and having a free end disposed materially beyond the pivot, a member projecting from the other of said plates having a latching end portion for movement along the inner curved surface of said tongue upon relative pivotal movement of the plates and for gradually increasing the tension of the tongue as the member moves toward the free end thereof, and an aperture in said tongue adjacent the free end thereof for receiving the latching end portion of said member and allowing the portion of the tongue bordering the aperture to spring into abutting relation with the member to stop and yieldably latch said plates in predetermined angular relation.

4. A hinge construction according to claim 3 together with a stop shoulder on the member to engage an edge of the aperture to preclude movement of the member beyond the free end of the tongue.

5. A hinge construction comprising a pair of pivotally connected plates, an arcuate resilient and yieldable tongue projecting in the form of a single curved strip from one of said plates in eccentric relation to the pivotal connection of the plates and having a free end disposed materially beyond the pivot in spaced relation to said plates, a lug on the other plate, a roller supported by the lug for movement along the inner con-

5

cave surface of the tongue upon relative pivotal movement of the plates, the roller gradually increasing the tension of the tongue in its movement toward the free end thereof, an aperture in the tongue adjacent its free end for reception of the roller to yieldably latch the plates in predetermined angular relation, and means on the lug embracing the roller for abutment with the tongue to preclude movement of the roller beyond the aperture and over the free end of the tongue.

6. A hinge construction according to claim 5 wherein said stop means comprises a shoulder on the roller supporting means for engagement with the rear edge of the aperture.

7. A hinge construction according to claim 5 together with a hood on the tongue supporting plate for receiving a portion of the roller when the plates are in one limit of relative movement.

8. A hinge according to claim 5, wherein said other plate is offset between its ends and the roller is supported by the offset portion of said plate for cooperative engagement with the uniformly curving tongue to gradually tension the tongue upon relative pivotal movement of the plates.

JOHN J. THOMAS.
